UNITED STATES PATENT OFFICE.

HARRY KNOX, OF WASHINGTON, PENNSYLVANIA.

WAGON-BODY.

No. 879,653.

Specification of Letters Patent.

Patented Feb. 18, 1908.

Application filed September 10, 1907. Serial No. 392,101.

To all whom it may concern:

Be it known that I, HARRY KNOX, a citizen of the United States of America, residing at Washington, in the county of Washington and State of Pennsylvania, have invented certain new and useful Improvements in Wagon-Bodies, of which the following is a specification, reference being had therein to the accompanying drawing.

10 This invention relates to wagon bodies, and its primary object is, to provide a wagon body which may be readily converted from a box-body, into a hay-rack, or vice versa.

15 The invention comprises a wagon-body consisting of longitudinal and transverse bed timbers the latter having their ends recessed and beveled, in combination with side board standards and slotted cleats for connecting said standards to the ends of the 20 transverse bars of the wagon bed, in such a manner as to permit the side-boards to be supported in either a vertical or inclined position.

25 The invention also includes removable end gates and means for supporting the same upon the wagon body.

30 The construction of the improvement will be fully described hereinafter, in connection with the accompanying drawings which form 35 a part of the specification, and its features of novelty will be set forth in the appended claims.

35 In the drawings:—Figure 1 is a side elevation of the device as arranged for use as a box body or bed, Fig. 2 is a top plan view of the same, Fig. 3 is an end elevation thereof, Fig. 4 is a top plan of the wagon body with its side-boards in inclined position to provide a hay rack, and, Fig. 5 is an end elevation 40 of the same.

45 The wagon bed consists of longitudinal beams 1 and a series of transverse bars 2, the latter having their ends beveled as shown at 3, and recessed to provide shoulders 4.

50 The longitudinal beams of the body are supported at their ends upon bolsters 5, to which are secured metallic straps 6 bent to provide sockets 7 and 8 for the purpose herein-after explained. The floor 9 consists of

55 boards secured upon the transverse bars 2, and the side boards 10 are secured to standards 11 which rest upon the projecting ends of the bars 2. The lower ends of the standards are recessed to form shoulders 11^a

55 which engage shoulders 11^b formed by recessing the upper surfaces of the bar 2 (Fig.

3.) To each side of each of the standards 11 is secured a metallic cleat 12 the lower ends of which depend below the bars 2 and are formed with elongated slots 13 to receive 60 bolts 14 which extend through the bars 2 and also through said cleats. The end gates 15 of the wagon are provided with standards 16 extending below the transverse bars 2 and having their lower ends recessed to 65 adapt them to fit the sockets 7 of the metal straps 6.

When constructed and arranged as thus far described the invention provides a wagon body of the box-type with vertical 70 sides and ends.

To convert the body into a hay rack the end gates 15 are removed, after which the sides 10 are turned outward to the position shown in full lines in Fig. 5, to engage the 75 shoulders 11^a with the shoulders 4 of the cross bars 2. The slots 13 in the cleats 12 permit of this movement, and the lower ends of the standards 11 rest upon the beveled ends 3 of the cross bars 2. Vertically extended end gates 17 having the lower ends 18 recessed to fit the sockets 8 of the straps 6 are then placed in position as shown in Figs. 4 and 5 thus completing the formation of a hay rack. It will be apparent that the slotted cleats 12 limit the outward movement of the sides 10, and in connection with the standards 11 maintain said sides at the desired inclination to support a load of hay. The sides of the vehicle bed may be readily 90 restored to the vertical position shown by dotted lines in Fig. 5, and the end gates shown in Figs. 1, 2 and 3 substituted for the gate shown in Fig. 5.

The invention includes all such variations in the details and minor features of construction as may fall within the terms and scope of the following claims.

Having fully described my invention what I claim and desire to secure by Letters Pat- 100 ent, is:

1. A vehicle body comprising a pair of longitudinal beams, cross bars supported thereon and having their ends extending beyond the beams, said ends having shoulders 105 formed therein, bolsters on which said longitudinal beams are supported, a bottom supported on said cross bars, sides for said body, standards to which said sides are secured, the said standards having shoulders at their 110 lower ends engaging shoulders in the upper faces of the cross bars when the standards

are in the vertical position, cleats secured to opposite sides of said standards extending below the cross bars and provided with slots, and pins carried by said cross bars and engaging in said slots, the said sides and standards being movable to an inclined position, the shoulders of the standards when the latter are inclined engaging the shoulders in the ends of the cross bars, and the pins in the cross bars engaging the extreme ends of the slots in said cleats.

2. A wagon body comprising a pair of longitudinal beams, cross bars supported thereon with their ends extending beyond the beams and provided with shoulders, a bottom mounted on the cross bars, sides for said body, and standards to which said sides

are secured, the said sides and standards being movable from a vertical position to an inclined position, the said standards in their vertical position resting on the cross bars and in the inclined position engaging the shouldered ends of said cross bars, cleats secured to the standards and having slots, and pins extending through the cross bars and engaging in said slots to secure the sides when in the inclined position. 20 25

In testimony whereof I affix my signature in the presence of two witnesses.

HARRY KNOX.
